UNITED STATES PATENT OFFICE.

ARTHUR J. MINOPRIO, OF STONEWALL, MISSISSIPPI, ASSIGNOR TO H. C. DEAR, OF ENTERPRISE, MISSISSIPPI.

COLLAPSIBLE POULTRY-COOP.

1,201,216.

Specification of Letters Patent. Patented Oct. 10, 1916.

Application filed May 5, 1915. Serial No. 26,026.

To all whom it may concern:

Be it known that I, ARTHUR J. MINOPRIO, a subject of the King of Great Britain, residing at Stonewall, in the county of Clarke 5 and State of Mississippi, have invented certain new and useful Improvements in Collapsible Poultry-Coops; and I do hereby declare the following to be a full, clear, and exact description of the invention, such as 10 will enable others skilled in the art to which it appertains to make and use the same.

This invention relates to new and useful improvements in collapsible poultry coops, and has for its principal object to provide 15 a device which, after having been shipped, may be folded so as to occupy a minimum amount of space in a car or other vehicle so that the cost of the return of the crate will be minimized.

Another object of the invention is to provide a poultry coop which will remain rigid 20 when opened and which is so braced that it is prevented from collapsing.

A further object of the invention is to provide a poultry coop provided with a 25 door in the front wall thereof so that the contents may be removed without the necessity of removing other coops which may be piled upon the top thereof.

With these and other objects in view, the invention consists in the novel combination and arrangement of parts which will be 30 fully set forth in the following specification and accompanying drawings, in which,

Figure 1 is a perspective view of a coop 35 constructed in accordance with this invention, Fig. 2 is a perspective view of the coop showing the first step taken in the folding of the same, Fig. 3 is a perspective 40 view similar to Fig. 2 showing the second step in the folding of the device, Fig. 4 is an end view in elevation showing the device in its folded position, and Fig. 5 is an end view in elevation showing the device 45 in its open position.

Referring to the drawings by characters of reference, the numeral 1 designates as an 50 entirety the front wall of the device comprising the strips 2 and 3 which extend longitudinally thereof and form the side edges of the said wall, these strips being connected by means of the uprights 4 and 5, and the brace bars 6 and 7 are secured intermediate the ends of the strips to form 55 a frame for the door 8 which is pivoted be-

tween the strips as clearly shown in Figs. 1, 2, and 3. A suitable catch 9 of any suitable construction is secured to the strips and is arranged to hold the door in its closed position. Secured to the strip 3 of 60 the frame forming the front wall 1 is a suitable flange 10 to which the top is hinged as will be more fully hereinafter described. A similar flange 11 is secured to the lower strip 2, and to this flange is secured the bottom wall which will be more fully herein- 65 after described. The flange 11 is of greater width than the flange 10 as clearly shown in the drawings and is so constructed to compensate for the width of the flange carried by the rear wall which co-operates with the flange 10.

The top wall of the device comprises two 70 separate frames, designated generally by the numerals 12 and 13, each of which comprises the side bars 14 and end bars 15. These frames 12 and 13 are hinged together as at 16 and the edge of the frame 13, which is not hinged to the frame 12, is hingedly 75 secured to the flange 10 in such a way that it will fold downwardly as illustrated in Fig. 3. The hinge securing the frame 13 to the flange 10 is designated by the numeral 17 and is placed on the under side of the 80 frame and flange.

The bottom wall of the coop comprises the two separate frames 18 and 19, each of which comprises the side strips 20 and end strips 21, and these frames, like the frames 12 and 13, are hingedly secured as at 2 so 85 that they will fold inwardly. Suitable 90 hinges 23 connect the frame 18 to the flange 11 so that the bottom will fold upwardly as indicated in Fig. 3.

The rear wall of the crate is designated 95 generally by the numeral 24 and comprises the strip 25 which is provided near each end with the upright 26. A central standard 27 is secured intermediate the ends of the strip 25 and forms a brace for the same. 100 A suitable flange 28 is secured to the upper edge of the strip 25 and hingedly connected to this flange as at 29 is the edge of the frame 12 opposite the one which is hinged to the frame 13. The edge of the frame 19 105 opposite the one which is hinged to the edge of the frame 18, is secured hingedly as at 30 to each of the uprights 26 and 27, and it will thus be seen that a coop is provided 110 which will collapse as illustrated in Fig. 3.

In order to form end closures for the coop and also to brace the same and hold it in its open position, the end walls designated generally by the numeral 31, are provided 5 and each of these walls comprises the top and bottom strips 32 and 33 which are connected to each other by the end strips 34. Suitable brace wires 35 are provided and extend from opposite corners of the frames 31 10 so as to prevent the same from becoming racked.

In order to hold the device in its folded and unfolded positions, there are provided the thumb screws 36 which are threaded

- 15 through apertures formed in the upright 26 of the rear wall 24 and engage in apertures formed in the end bars 34 of the frames 31. These thumb screws are arranged to be released so that the end walls may be swung 20 into the position shown in Figs. 2 and 3 to enable the device to be folded. Suitable screw threaded apertures are formed in the end faces 21 of the frames 18 and 19, and these openings are arranged to align with the 25 openings through which the thumb screws 36 extend so that when the device is in its folded position, the thumb screws will engage in the threaded apertures and hold the device in place.
- 30 It will be apparent from the foregoing that in use, the device is normally opened as shown in Fig. 1. When it is desired to re-ship the device and return it to the shipper, the end walls 31 are pressed inwardly as 35 illustrated in Fig. 2 and when they have been forced clear back so that they engage the front wall as illustrated in Fig. 3, the top and bottom walls are then folded inwardly on their hinges so that they assume 40 the position shown in Fig. 3, and upon pressing the front and rear walls toward each other, it will be apparent that the device may be closed so that it will give the appearance

shown in Fig. 4. In this way it will be evident that the amount of space taken up by 45 the crate when folded is considerably less than that occupied when the crate is in its open position and thereby much saving in the cost of reshipping empty crates is effected.

50 While in the foregoing there has been shown and described the preferred embodiment of this invention, it is to be understood that such changes may be made in the combination and arrangement of parts as will fall 55 within the spirit and scope of the invention as claimed.

What is claimed is:

A collapsible poultry coop comprising front and rear walls, a door hinged to said 60 front wall, flanges formed on the upper and lower edges of the front wall and extending in the direction of said rear wall, the lower flanges extending to a point beyond the upper flange, a flange formed on the upper 65 edge of the rear wall and extending in the direction of the front wall, a bottom consisting of a pair of frames hinged together and to the lower flange of the front wall and to the lower edge of the rear wall and adapted 70 to be folded upwardly in the direction of the flange of the rear wall, a top consisting of a pair of frames hinged together and the upper flange of the front wall and the flange of the rear wall and adapted to be folded downwardly 75 in the direction of the lower flange of the front wall, and end walls hinged to the ends of the front wall and adapted to be folded inwardly to fold the top and bottom frames.

80 In testimony whereof I affix my signature in presence of two witnesses.

ARTHUR J. MINOPRIO.
